FOOD PACKAGING TRAY OR SIMILAR ARTICLE

Leo Cesareo, 7 Killman Hill Road, Boxford, Mass.

Filed May 18, 1964, Ser. No. 80,039

Term of patent 14 years

(Cl. D58—12.6)

FIG. 1 is a perspective view of a food packaging tray or similar article, showing my new design;

FIG. 2 is an end elevational view thereof; and

FIG. 3 is a top plan view thereof.

I claim:

The ornamental design for a food packaging tray or similar article, as shown.
